UNITED STATES PATENT OFFICE.

WILLIAM H. HOLAHAN, OF CHICAGO, ILLINOIS.

BICYCLE SEAT-POST.

SPECIFICATION forming part of Letters Patent No. 650,393, dated May 29, 1900.

Application filed June 5, 1899. Serial No. 719,421. (No model.)

To all whom it may concern:

Be it known that I, WILLIAM H. HOLAHAN, of Chicago, in the county of Cook and State of Illinois, have invented certain new and useful Improvements in Bicycle Seat-Posts, of which the following is a full, clear, and exact description, reference being had to the accompanying drawings, forming a part of this specification, in which similar letters of reference in the different figures indicate like parts.

One object of my invention is to so construct an expanding self-locking device for use in connection with bicycle seat-posts and handle-bar stems that the expanding elements may serve as a reinforcement to the tube into which they are inserted.

A further object is to so construct a fastening device to be used, preferably, in connection with handle-bars that the expansion members may be rigidly and positively secured in position, so as to insure the same against accidental displacement, all of which is hereinafter more particularly described and claimed.

In the drawings, Figure 1 is a longitudinal vertical sectional view of my improved seat-post and part of the bicycle-frame. Fig. 2 is a like view showing a modified construction. Fig. 3 is a sectional view taken upon the line 3 3, Fig. 1. Fig. 4 is a sectional view taken upon the line 4 4, Fig. 1. Figs. 5 and 6 are views corresponding to those shown in Figs. 1 and 2, showing modifications of said invention. Fig. 7 is a plan view of the seat-post stem as it would appear when the top bar is removed; and Fig. 8 is a vertical sectional view of a modified construction, showing said invention applied to a handle-bar, with means for positively securing the expansion members in position.

Referring to the drawings, *a* represents the usual bicycle-frame or supporting-tube, while *b* indicates the tubular seat-post stem adapted to be received therein. That portion of the stem which extends above the receiving socket of the frame is flattened, as shown at *c*, (better represented in Figs. 4 and 7,) so as to form an elongated opening, into which may be fitted two flat expansion members *d* *e*.

Said expansion members are formed from blanks of sheet-steel preferably about three-sixteenths of an inch in thickness, and the

outer faces are intended to be parallel with each other, so that when placed within the tubular stem they may fit against the opposite sides thereof, as shown in the drawings. An elongated opening or slot *f*, Figs. 1, 5, and 6, is formed in the top of the expansion member *d* for the reception of a screw or rivet *g*, (better shown in, Fig. 4,) which passes through the top bar *h* and also through a bore in the part *c*, thus forming a pivot or fulcrum for the top bar, to which the saddle is intended to be secured in the usual way. That portion of the top bar which passes over the part *c* of the stem is made U-shaped in cross-section, thus forming flanges *i* *i*, (better shown in Fig. 4,) which extend down upon opposite sides of the part *c*, as shown. A secondary screw or rivet *j* is inserted through the top bar *h* and through a bore in the upper end of the expansion member *e*, a notch *k* being formed in the part *c* for the reception of said screw, said notch being made sufficiently deep to permit the rivet *j* to extend to its lowest desirable limit without being arrested by the part *c*.

The expansion members *d* *e* are provided with means, or their meeting faces are so formed with respect to each other, that when said members are moved longitudinally in opposite directions their outer faces are caused to be brought nearer together or moved farther away from each other in parallel planes. This result is accomplished, preferably, by forming upon said faces a series of reverse inclines, or, in other words, a series of surfaces which are inclined in opposite directions with respect to each other in the respective members, as represented at 1 in Figs. 1 and 6. In the former figure said inclined faces are represented by sinuous lines, while in the latter they assume a zigzag form. When constructed in either manner, one member forms a counterpart to the other, and when two are fitted together, so that the opposite faces touch from end to end, as shown, it is manifest that the outer faces are at a minimum distance from each other. Said members should be of such size that when thus adjusted the outer faces will fit accurately within the tubular stem. With the rivet *g* extending through the part *c* and member *d* it is obvious that the latter will be maintained in a stationary position,

while the member *e* may be moved up or down by exerting pressure upon one or the other end of the top bar *h*, and in whichever direction the bar *h* is moved, the rivet *g* acting as 5 a fulcrum, the outer faces of the members *d* *e* are caused to separate in parallel planes, and inasmuch as the wedging action is a powerful one the pressure against the diametrically-opposite sides of the tube *b* causes the 10 latter to expand into an oval form, as indicated in dotted lines in Fig. 3, thereby firmly securing the stem within the supporting-tube *a*. The expansion necessary to lock the stem in place is necessarily very slight, and, assuming 15 the parts to be properly fitted, would be scarcely perceptible, and hence upon releasing the pressure the stem would assume its normal shape, thus enabling it to be readily withdrawn from the supporting-tube. This 20 construction possesses the important advantage that it enables a T top bar to be used, so that the saddle may be adjusted either in the front or rear of the stem, the downward pressure in the former position serving to depress and in the latter to raise the member *e* 25 and in both cases to lock the seat-post in the socket.

In Fig. 2 I have shown a modification of 30 said device in which the expanding members *d*² *e*² are tapered in opposite directions. This construction necessitates the placing of the saddle upon one end only of the top bar, a pressure upon the opposite end serving to produce an unlocking action. In said last-named view I have also shown a means for 35 an additional adjustment of the expanding members in order to cause the proper expansion under varying conditions, while maintaining the bar *h* substantially horizontal 40 when the parts are locked. In order to accomplish this result, I shorten the member *d*² and insert a solid block *m*, of metal, in the upper end of the stem, into which block is tapped a rod *n*, which is extended through 45 lugs *o* *p*, formed upon or secured to the side of the member *d*². The lug *o* is detachable and is inserted between shoulders *q* *r*, formed upon said rod. A lug *s* is bent inwardly from the lower end of the tube *b* and serves as a 50 guide for the rod *n*, which is passed loosely through it. The lower end of the rod is provided with a screw-head *t* to permit adjustment. As the rod is turned in one or another direction the member *d* is raised or lowered, 55 thus providing for any extreme in adjustment which may be desired.

In Fig. 5 I have shown a still further modification in which a series of inclined faces *u* are formed upon the member *d*³, all of which 60 are oblique to the straight inner face *v* of the member *e*³. Within the spaces or pockets between the two I place a series of hardened-steel balls *w*, which are preferably held in place by slightly grooving the respective surfaces upon which they bear. When the balls 65 are in the respective positions shown, it is

obvious that a downward pressure upon the outer end of the top bar will cause them to roll down the incline, thereby separating the members *d*³ *e*³ and producing the desired locking. 70

Fig. 8 shows my improved expanding device as I would construct it for application to the stem *b*¹ of an ordinary handle-bar *b*². The expansion members *d*¹ *e*¹ are secured to the handle-bar by means of bolts or rivets, as 75 shown, and are so adjusted that when the stem is inserted within its socket and the handle-bar is placed in a horizontal position the stem is expanded. A ferrule or band *b*³ is brazed upon or otherwise permanently attached to the handle-bar, said band being tapered, as shown at *b*⁴, and slotted at *b*⁵ to receive the upper or flattened portion of the stem. Said stem is also provided with a lug *c*', which is adapted to fit loosely within the 80 notch formed in the band *b*³. The handle-bar is threaded at *b*⁶ to receive a nut *b*⁷, which is reamed out, as shown, to fit the tapered end of the band. When the nut is screwed into 85 position, the lug *c*' is engaged thereby, which serves to positively lock the handle-bar in place until the nut is removed, when the tilting of the handle-bar will serve to disengage the expansion members in the manner described. 90

An important and obvious advantage of my improved device is that the expansion members serve as a powerful reinforcement to the stem of the seat-post, while the latter in turn supplements said members and especially provides against their lateral displacement and serves to rigidly secure the top bar in place. 95

Having thus described my invention, I claim—

1. A device of the class described, in which 105 is combined a tubular stem adapted to fit within the supporting-tube of the frame, a bar pivoted upon the upper end of said tubular stem, a flat expansion member rigidly secured within said tubular stem, a secondary 110 flat expansion member having its upper end pivotally attached to said bar, said member being arranged to move longitudinally within said stem in the same plane with said primary member, the two being disposed to bear sub- 115 substantially throughout their length upon opposite inner longitudinal surfaces of said tubular stem, and means for causing said expansion members to expand or separate laterally when pressure is applied to one end of said 120 bar, substantially as described.

2. A device of the class described, in which 125 is combined a tubular stem adapted to fit within the supporting-tube of the frame, a bar pivoted upon the upper end of said tubular stem, an expansion member rigidly secured within said tubular stem, a secondary 130 expansion member having its upper end pivotally attached to said bar, said member being arranged to move longitudinally within said stem, means for causing said expansion members to expand when pressure is applied

to one end of said bar, a lug formed upon and extending laterally from said tubular stem, and a nut upon said bar for engaging said lug and positively locking said expansion members in a clamped position, substantially as described.

5 In testimony whereof I have signed this

specification, in the presence of two subscribing witnesses, this 2d day of June, 1899.

WILLIAM H. HOLAHAN.
